UNITED STATES PATENT OFFICE.

HULEN MONROE HARRISON, OF CHICAGO, ILLINOIS.

DESIGN FOR A CASING FOR DRINK-DISPENSING MACHINE.

Application filed March 18, 1929. Serial No. 30,513. Term of patent 14 years.

To all whom it may concern:

Be it known that I, HULEN MONROE HARRISON, a citizen of the United States, residing at Chicago, in the county of Cook, and State of Illinois, have invented a new, original, and ornamental Design for Casing for Drink-Dispensing Machine, of which the following is a specification, reference being had to the accompanying drawings, forming a part thereof.

In the drawings:

Fig. 1 is a front elevation of a casing for drink dispensing machine, showing my new design; Fig. 2 is a side elevation thereof; Fig. 3 is a top view; Fig. 4 is a section on the line 4—4 of Fig. 2; and Fig. 5 is a section on the line 5—5 of Fig. 2.

I claim:

The ornamental design for a casing for drink dispensing machine, as shown.

HULEN MONROE HARRISON.
